Patented Dec. 14, 1915.

UNITED STATES PATENT OFFICE.

ROBERT T. BALDWIN, OF KLAMATH FALLS, OREGON.

SPRAYING DEVICE.

1,163,635.

Specification of Letters Patent. Patented Dec. 14, 1915.

Application filed May 28, 1915. Serial No. 31,035.

To all whom it may concern:

Be it known that I, ROBERT T. BALDWIN, residing at Klamath Falls, in the county of Klamath and State of Oregon, have invented a new and Improved Spraying Device, of which the following is a specification.

My invention has reference to that class of portable spraying devices or means adapted for being connected with a source of fluid supply, water or air, under pressure, and in which the fluid supply is caused to commingle with the soluble material as it passes to the discharging nozzle and is directed onto plants, trees, shrubbery, etc., and my said invention primarily has for its object to provide a spraying device of the general character stated, of a simple and economical construction, and of few parts that can be conveniently manipulated for effectively serving their intended purposes.

With other objects in view that will be hereinafter referred to my invention embodies the peculiar construction and novel arrangement of the parts hereinafter explained, specifically pointed out in the appended claims and illustrated in the accompanying drawings, in which—

Figure 1 is a vertical longitudinal section of my improved spraying device. Fig. 2 is a horizontal section thereof on the line 2—2 of Fig. 1. Fig. 3 is a perspective view of one of the spraying solution blocks hereinafter referred to.

The body of the sprayer is in the nature of a cylinder 4, the upper and lower ends of which are externally threaded to receive the upper and lower cap members 20 and 8. Cap member 20 has a contracted threaded upper end that receives a spraying nozzle 1, as shown; and its lower end is threaded as at 3 for threading onto the upper end of the cylinder 4.

9 designates an elbow shaped member that forms a fluid connection for joining the sprayer with the source of fluid supply and the said member includes a neck 90 that is externally threaded as at 91 to fit into the threaded passage 80 in the lower cap 8.

6 is a perforated tube threaded at the lower end for removably connecting it to the threaded neck 90 of the fluid connection 9 and the said tube 6, which extends the full length of the cylinder 4, has its upper end projected to discharge into the nozzle 1, as is clearly shown in Fig. 1 of the drawing.

7 designates a soluble material in the na-

ture of a block or cartridge made of suitable composition, chemically hardened, and which is slowly dissolved by the passing fluid, and the said block is of a diameter to 60 snugly fit within the cylinder 4 and has a central bore 70 for slidably engaging the perforated tube 6.

10 designates a handle on the lower end of a valve rod 16 that slides in a stuffing box 11 in the connection 9 and extends up into the tube 6 and carries a ball valve 5 slidably mounted in the said tube 6.

14 designates a stop flange within the tube 6 that prevents the ball valve from choking 70 the nozzle 1 in case it should become loose from the rod or stem 10, or the fluid pressure tend to force it to the upper end of the tube 6.

From the foregoing taken in connection 75 with the drawing, the construction of my improved spraying device will be readily understood.

By reason of mounting the soluble block 7 within the cylinder 4 and on the tube 6, 80 as shown, the fluid that enters the cylinder, as it passes into the lower end of the tube 6 discharges through the perforations 60 into the cylinder and seeps through the soluble block 7 and, mixed with the solution it 85 passes back into the tube 6 above the valve 5 when the latter is adjusted as in Fig. 1.

By providing a central tube 6 that extends the full length of the cylinder, mounting the soluble block 7 and providing a valve 90 control, as shown, the force and volume of fluid entering the cylinder to mix with the soluble block can be readily regulated, it being understood that by adjusting the valve 5, to the position shown by dotted lines X 95 on Fig. 1, the water that passes into the cylinder, by reason of passing back into the tube 6 before it rises against the block 7, will become less saturated with the soluble substance than is the case when the ball 100 valve 5 is located above the block 7, as shown in full lines in Fig. 1. Again, by reason of using the material that is to be placed in solution, in block form, a plurality of such blocks may be readily mounted on the tube 105 6 within the cylinder 4 when a very strong spray solution is desired.

The several parts that constitute my spray device may be readily disconnected for cleaning and quickly reassembled.

What I claim is:

1. The combination of a cylinder having a

nozzle at one end and inlet connection at the other end adapted for being connected to a source of fluid supply, a perforated tube that extends the full length of the cylinder whose 5 upper end discharges into the nozzle and whose lower end joins the inlet connection, a soluble chemical block fitting within the cylinder between the said cylinder and the perforated tube and a body slidably longitudinally within the perforated tube to act as a 10 dam or cutoff.

2. The combination of a cylinder having a nozzle at one end and inlet connection at the other end adapted for being connected to a source of fluid supply, a perforated tube that extends the full length of the cylinder whose upper end discharges into the nozzle and whose lower end joins the inlet connection, a soluble chemical block fitting within the cylinder between the said cylinder and the perforated tube, and a valve slidably mounted within the perforated tube for controlling the flow of fluid through the said tube, said valve having a rod that extends 25 through and outside of the fluid connection at the lower end of the cylinder.

3. A spraying device comprising a cylinder having a discharging nozzle at one end, a pipe connection at the other end for joining the same with a source of fluid supply, a perforated tube within the said cylinder detachably connected with the supply pipe connection, a valve slidably in the tube whose rod passes through the pipe connection and 35 a soluble chemical block mounted on the perforated tube and engaging the cylinder.

4. A spraying device comprising a cylinder, a cap member detachably mounted on the upper end of the said cylinder and having a discharging nozzle, a cap member removably connected with the lower end of the cylinder, a pipe connection detachably mounted on the said lower cap and comprising a tube whose upper end extends into the cylinder and whose lower end is adapted to be connected with the source of the fluid supply, a perforated tube mounted on the

upper end of the said pipe connection, a soluble chemical block slidably mounted within the cylinder and on the perforated tube and a slideable valve within the perforated tube and a stem for the slideable valve that passes down through the pipe connection and terminates in a handle.

5. A spraying device comprising a cylinder, a cap member detachably mounted on the upper end of the said cylinder and having a discharging nozzle, a cap member removably connected with the lower end of the cylinder, a pipe connection detachably mounted on the said lower cap and comprising a tube whose upper end extends into the cylinder and whose lower end is adapted to be connected with the source of the fluid supply, a perforated tube mounted on the upper end of the said pipe connection, a soluble chemical block slidably mounted within the cylinder and on the perforated tube, a slideable valve within the perforated tube, a stem for the slideable valve that passes down through the pipe connection and terminates in a handle, and means in the upper end of the perforated tube for limiting the upward movement of the said valve.

6. The combination with a cylinder, a cap member removably closing its front end, said cap member including a spraying nozzle, a cap member removably closing the other end of the cylinder, a pipe connection carried by the last named cap member adapted for joining with the source of fluid supply, a perforated tube removably connected with the said pipe connection and extended the full length of the cylinder and adapted to discharge into the spraying nozzle, a soluble chemical block slidably mounted in the cylinder between the said cylinder and the perforated tube, a valve slidably within the perforated tube and having a stem that extends through the pipe connection and terminates in an operating handle, and means within the tube for limiting the upward movement of the said valve as set forth.

ROBERT T. BALDWIN.
